UNITED STATES PATENT OFFICE

2,098,218

BOBBIN AND METHOD OF PRODUCING THE SAME

Dickerson G. Baker, Holyoke, Mass., assignor to
The American Thread Company, New York,
N. Y., a corporation of New Jersey

Application December 16, 1931, Serial No. 581,824
Renewed April 28, 1937

3 Claims. (CL. 112—251)

My invention relates to bobbins for sewing machine shuttles and to a method of producing the same, and has for its object the production of a novel and improved bobbin of this character.

5 The following is a description of my invention, reference being had to the accompanying drawing, in which:

Figure 1 is a view in perspective of my improved bobbin in its preferred form;

10 Fig. 2 is a longitudinal sectional view on an enlarged scale, taken on the line 2—2 of Fig. 1;

Fig. 3 is a detail sectional view on an enlarged scale corresponding to a portion of Fig. 2;

15 Fig. 4 is a sectional view, taken on the line 4—4 of Fig. 3;

The bobbin illustrated in the drawing is of the type of the one described and claimed in the patent to R. V. Snyder and Malcolm Curry, "Bobbin and method of producing the same", No. 20 1,481,243, dated January 15, 1924.

As shown, the bobbin is provided with a tubular core 2 on which is a cross-wound mass of thread 4. Fitted on the ends of the core in close contact with the ends of the thread mass, are annular disks 6 of resilient paper.

25 In accordance with the present invention, the core is preferably made of sheet metal, such as aluminum, and may be formed either as a split tube or a seamless tube.

30 In the form shown in the drawing, after the disks 6 are placed on the ends of the core against the ends of the mass, the ends of the core are upset or swaged so as to hold the disks in place. A series of projections 8 spaced circumferentially about the core, are then struck outwardly so as to cause them to dent into the inner edge of the inner periphery of the disks.

35 With this construction it will be apparent that the disks are securely gripped between the swaged ends of the core and the projections 8 so as to hold the disks in position axially of the core

and prevent them from moving inwardly or getting out of place as the thread is unwound from the core. Also the indenting of the projections into the disks securely hold the disks from turning with relation to the core.

5 As will be evident to those skilled in the art, my invention permits various modifications without departing from the spirit thereof or the scope of the appended claims.

What I claim is:

10 1. In a filled bobbin having a tubular core having thread cross-wound thereon in a mass, and disks of resilient material on the ends of said core, the improvement which comprises said core being provided at each end with a series of outwardly struck projections indented into the inner edge of the inner periphery of the associated disk, and the ends of the core being swaged so as to secure the disks against the ends of the thread mass.

20 2. The method of forming a filled bobbin which comprises cross-winding thread into a mass on a tubular core of sheet metal, placing annular disks on the ends of the core against the ends of the mass, swaging the ends of the core to hold the disks against the mass, and forming a plurality of spaced outward projections in the sheet metal core against the inner edge of the inner periphery of each of the disks, so as to cause said projections to be indented into the 30 disk.

3. The method of forming a filled bobbin which comprises winding thread into a mass on a tubular core of sheet metal, placing annular disks on the ends of the core against the ends of the 35 mass, swaging the ends of the core to hold the disks against the ends of the mass, and thereafter forming outward projections on the core so as to cause the disks to be held between said projections and the swaged ends of the core.

DICKERSON G. BAKER.

CERTIFICATE OF CORRECTION.

Patent No. 2,098,218.

November 9, 1937.

DICKERSON G. BAKER.

It is hereby certified that error appears in the printed specification of the above numbered patent requiring correction as follows: Second column, line 23, claim 2, for the word "annual" read annular; and that the said Letters Patent should be read with this correction therein that the same may conform to the record of the case in the Patent Office.

Signed and sealed this 25th day of January, A. D. 1938.

(Seal)

Henry Van Arsdale,
Acting Commissioner of Patents.
